aware

Application September 28, 1937, Serial No. 166,039

3 Claims. (Cl. 132—38)

This invention relates to hair devices, and more especially to foundation frames for supporting the wearer's hair in a roll.

Among the objects of this invention are to provide a foundation frame of extremely light weight that can be handled and worn comfortably, that may be pinned in the hair and to which the hair may be pinned by means of conventional hairpins, that is stiff or semi-stiff but flexible and resilient, and that may be easily manipulated to dress and support the hair in a roll or puff.

According to my invention, I provide a foundation frame for use in dressing women's hair, which frame is made of a tube of braided or woven horsehair, artificial horsehair or similar relatively stiff but resilient flexible material.

A feature of my invention is that the ends of the tube are inturned and bound to avoid any discomfort to the wearer that might be caused by protruding loose ends or threads of the relatively stiff material.

The accompanying drawing illustrates a preferred embodiment of the invention, in which:

Figure 1 is a side elevation of my improved foundation frame;

Fig. 2 is a longitudinal cross-sectional view thereof; and

Fig. 3 is a transverse sectional view taken on the line 3—3 of Figure 1.

The foundation frame comprises a body 10 in the form of an elongated tube, preferably seamless, made of relatively stiff but flexible and resilient material, such as horsehair, artificial horsehair, and the like. The material is braided or woven to provide a body of open mesh construction adapted to permit of penetration of hairpins therethrough.

The ends of the tubular body 10 are gathered and bound by clasps 11 or other suitable binding

means, and are turned in, as best seen in Fig. 2, to form inturned portions 12 of substantially conical shape in cross-section at each end of the body.

The inturned portions serve to reenforce the ends of the tube and provide ends of somewhat increased stiffness that may be conveniently held between the fingers. They further serve to prevent the material of the tube from unraveling or fraying and to prevent any loose ends from protruding beyond the circumference of the tube with consequent inconvenience in handling and discomfort in wearing.

The device may be used either as a form around which the hair may be wound into a roll, or as a foundation around which the loose ends of the hair may be neatly tucked to dress the hair in a roll or puff. In either case, the foundation frame may be fastened to the hair and the hair secured on the frame by means of hairpins or the like.

What I claim is:

1. A foundation frame for supporting a hair roll comprising a cylindrical tube of substantially uniform diameter throughout made of relatively stiff resilient open mesh material, said tube having inturned ends of conical form.

2. A foundation frame for supporting a hair roll comprising a cylindrical tube of substantially uniform diameter throughout made of relatively stiff resilient open mesh material, said tube having inturned ends of conical form the inner extremities of which inturned ends are bound.

3. A foundation frame for supporting a hair roll comprising a cylindrical tube of substantially uniform diameter throughout made of relatively stiff resilient open mesh material, said tube having inturned ends of conical form the inner extremities of which inturned ends are bound with clasps.

WILLIAM HUPPERT.
